UNITED STATES PATENT OFFICE.

LEWIS H. BOWMAN, OF WALLA WALLA, WASHINGTON.

CAR-VENTILATOR.

SPECIFICATION forming part of Letters Patent No. 665,169, dated January 1, 1901.

Application filed November 9, 1899. Renewed October 29, 1900. Serial No. 34,804. (No model.)

To all whom it may concern:

Be it known that I, LEWIS H. BOWMAN, a citizen of the United States, and a resident of Walla Walla, in the county of Walla Walla 5 and State of Washington, have invented a new and Improved Car-Ventilator, of which the following is a full, clear, and exact description.

This invention relates to improvements in ventilators for cars, the ventilator being in 10 the form of a fan adapted by its rotation to cool the atmosphere and to drive floating dust from the car; and the object is to provide, in connection with the ventilating-fan, a motor operated by the current of wind when the car 15 is in motion.

I will describe a car-ventilator embodying my invention and then point out the novel features in the appended claims.

Reference is to be had to the accompanying 20 drawings, forming a part of this specification, in which similar characters of reference indicate corresponding parts in all the figures.

Figure 1 is a section on the line 1 1 of Fig. 2 of the ventilator embodying my invention. 25 Fig. 2 is a section on the line 2 2 of Fig. 1, and Fig. 3 is a bottom plan view of the ventilating-fan and its support.

Referring to the drawings, 1 designates the roof of a car, on which is mounted a turret 2, 30 open at its opposite sides. Mounted to rotate in the turret is a motor-fan comprising cup or spoon shaped blades 3, mounted on arms 4, extended outward from a hub formed of sections 5 and 6. The hub-section 5 has an 35 exterior thread to engage with an interior thread formed in the hub-section 6, which at its lower end has an annular channel to receive bearing-balls 7, said bearing-balls being supported in a cup-shaped ring 8, secured 40 to the inner side of the car-roof. When in position, the hub-section 5 is prevented from movement relatively to the section 6 by means of a set-screw 9, which passes through one of the arms 4 and engages in a recess formed in 45 the upper end of the section 6. A shaft 10 has screw-thread engagement with the hub-section 5, as clearly indicated in Fig. 1, and this shaft extends downward through the cup 8, and at its lower end it has an annular ring 50 11, upon the upper surface of which bearing-balls 12 are arranged in a ring-like cup 13,

attached to straps or arms 14, bolted to the roof of the car.

Mounted on an angular portion 15 of the shaft 10 is a fan, consisting of outwardly-extended blades 16, which are arranged at a transverse incline.

For the purpose of holding the fan from rotation when desired I employ a locking device, here shown as consisting of a bolt 17, 60 movable through lugs formed on one of the straps 14 and normally held inward to engage in a notch in the portion 11 of the shaft 10 by means of a spring 18. To disengage the bolt from the shaft, the bolt is to be drawn 65 outward, and it may be held in its outer position by engaging its crank end 19 with the outer side of a lug 20 on the strap 14.

In operation as the car is moving along the current of air passing through the turret will 70 cause the motor-fan to rotate rapidly, and this of course will cause the ventilating-fan to rotate rapidly in the car; but the turret may be dispensed with. I prefer to use it, however, as it not only directs the current of 75 wind directly to the motor-fan, but it serves as a housing or protection for said fan.

Having thus fully described my invention, I claim as new and desire to secure by Letters Patent—

1. In a car-ventilator, the combination of a hub formed of sections detachably secured together, one of the sections being provided with arms, blades secured to the arms in position to be revolved by the wind, a shaft having 85 one end mounted in a bearing and its other end detachably secured to the hub, and a fan mounted upon said shaft, substantially as described.

2. In a car-ventilator, the combination of a hub formed of sections, one section being internally screw-threaded and the other externally screw-threaded and provided with outwardly-extending arms and a threaded bore, means for locking the sections of the hub together, blades carried by the arms of the hub in position to be revolved by the wind, a shaft having one end mounted in a bearing and its other end screw-threaded and screwing into the bore of the hub-section, and a fan on the 95 said shaft, substantially as described.

3. A ventilator, comprising a fan arranged

on the inner side of the car-roof, a shaft on which the said fan is mounted, said shaft being extended through the car-roof and screw-threaded, a hub having connection with the 5 screw-thread of the shaft and formed of two sections detachably secured together, one section being provided with arms and the other with a raceway for balls, spoon-shaped blades 10 on the arms in position to be revolved by the wind, bearing-balls in the raceway of the lower hub-section, a ring-shaped cup secured to the inner side of the car-roof and supporting said bearing-balls, and bearing-balls for the lower portion of the said shaft, substantially as specified.

4. In a car-ventilator, the combination with the roof of a car, and a turret thereon, of a hub mounted in the roof of the car and extending into the turret, said hub being provided with a threaded bore and outwardly-extending arms, blades secured to said arms 15 in position to be revolved by the wind, arms

secured to the under side of the roof and provided with a bearing, a shaft having one end mounted in the bearing and its other end 25 screw-threaded and screwing into the bore of the hub, a fan on said shaft, and means for locking the shaft stationary, substantially as described.

5. In a car-ventilator, the combination with 30 a fan-shaft having one end mounted in a support, and its other end threaded, of a hub formed of sections, one section being internally screw-threaded and the other exteriorly screw-threaded and provided with arms and a threaded bore, blades secured to the arms in position to be revolved by the wind, and a set-screw passing through one of the arms of the hub-section and engaging the other hub-section, substantially as described.

LEWIS H. BOWMAN.
